UNITED STATES PATENT OFFICE

ROSE FREED, OF SAN DIEGO, CALIFORNIA

UNDERWEAR

Application filed October 23, 1929. Serial No. 401,861.

My invention relates to underwear for women and misses, and the garment is of the combination or convertible type that is adapted for use either as a skirt, or as a combined skirt and pair of bloomers, and when employed or worn as the latter garment, a sanitary napkin may be employed or worn for sanitary, personal, use.

The garment is of the slip-over type, that is, it is slipped over the head of the wearer when dressing, or it may with equal facility be stepped into, or stepped out of, when desirable.

The garment includes a semi-divided skirt, that is, a skirt having a divided front portion, and a shield-panel or skirt-panel, to close over the divided front portion of the skirt; and also a detachable and removable bloomer-panel that is attached to the skirt when the garment is to be used as a combined skirt and pair of bloomers. In addition, a sanitary pad may be supported in place by the bloomer-panel, when required.

The various parts of the garment are combined and arranged in such manner as to insure convenience and facility in the conversion of the garment for different uses, and to assure comfort to the wearer at all times.

In the accompanying drawings I have illustrated one complete example of the physical embodiment of my invention wherein the parts are combined and arranged according to the best mode I have thus far devised for the practical application of the principles of my invention.

Figure 1 is a perspective view of the garment showing it in use as combined skirt and bloomer, parts being illustrated by dotted lines.

Figure 2 is an enlarged view of the garment, flattened out, and showing the parts in dotted lines that are otherwise invisible.

Figure 3 is a plan view of the removable bloomer-panel, detached.

Figure 4 is a flat view of the garment as used for a skirt.

Figure 5 is a view of part of the skirt with the skirt-panel removed and part of the divided-front broken away for convenience of illustration.

The skirt 1 is fashioned in various sizes, of course in suitable materials and different colors, and is preferably Shirred at its open top and provided with an elastic band indicated by dotted lines, as 2 in Figures 2 and 4, but other means may be employed if desired to support the skirt.

At its front portion the skirt is divided or cut out at the center, from the bottom edge, up, a suitable distance, and the opposed free edges 3 and 4 of the front-divided skirt fall inwardly and around the legs of the wearer. This arrangement of the skirt provides for the leg portions of the bloomers when the skirt is worn or converted for that use. Garter supports may be attached to these leg portions of the skirt for supporting hosiery, and at the same time for holding the bloomer-leg in position around the front portion of the leg.

At the upper edge of the divided-front of the skirt, a central, downwardly projecting tab 5 is fashioned, and at opposite sides of the tab, curved notches 6, 6, are cut out of the skirt in order that the top edge of the divided-front may readily conform to the contour of the wearer.

In a horizontal line, on the tab and also on the upper edge of the divided-front adjacent the notches 6, 6, are secured heads 7 that form members of a snap fastening, and these heads are adapted to co-act with complementary socket-heads 8 that are secured along one edge of the detachable and removable bloomer-panel 9. This bloomer panel as seen in Figure 3 is fashioned with two parallel straight edges, and laterally, curved portions, or side edges that bulge outwardly, while near the straight edges these lateral edges curve inwardly, to adapt the panel for use as in Figure 1. In Figure 1 the bloomer panel is indicated as passing downwardly from the front, under, and up to the rear, and it is attached along its straight edges at both front and rear.

This bloomer-panel 9, when used, converts the garment into a combination skirt and bloomer, and it will be apparent that when desired, this panel may be constructed and adapted for sanitary purposes and special

use by the wearer. Or the panel may be of the same material as the skirt to match the latter and thus provide a comfortable, neat and attractive combination garment. When 5 used in either manner, a number of the panels are furnished with the garment, and of course the panels may be and are, laundered separately from the garment.

On the inside of the back of the skirt a 10 horizontal braid or tape 10 is stitched, and at 11 snap-heads are secured to this tape, and the bloomer-panel, at the rear, is attached to the skirt or to the braid on the skirt by means of the complementary socket-heads 12 that 15 co-act with the snap heads 11. The socket-heads 12 are attached along one of the straight edges of the panel and at the side of the panel opposite to that to which the socket heads 8 are attached.

20 It will be apparent that by connecting or fastening the narrowed front of the bloomer panel outside of the skirt, but under the skirt panel, the wearer may with greatest convenience, draw the panel through the front opening of the skirt and then quickly fasten the front edge of the bloomer panel to the skirt. The fastenings of the bloomer panel and the skirt are snapped together by pressing inwardly against the abdomen of the wearer, 25 which affords the resistance required in snapping the fasteners together.

While I have shown the well known type of snap-fasteners, or glove fasteners for securing the bloomer-panel in place, it will be understood that other detachable fastening means may be employed for joining the panel 30 with the skirt when desired.

The divided-front part of the skirt is covered by the use of a panel 13 fashioned in 40 suitable shape, and preferably attached permanently to the skirt to form a skirt-panel. Across its upper straight edge, the panel is stitched at 14, or it may be otherwise attached to the skirt to form a part thereof and cover 45 the open-front or divided-front of the skirt, and as seen in Figure 4 the garment is fashioned as a complete and usual type of skirt.

From the above description taken in connection with my drawings it will be apparent 50 that I have provided a garment that embodies simplicity and comfort, and one which readily conforms to the shape of the figure of the wearer; the parts of the garment are so combined and arranged that they may with 55 facility be laundered; and it is obvious that the parts may be interchanged with convenience in converting the garment for its various uses.

Having thus fully described my invention, 60 what I claim as new and desire to secure by Letters Patent is:—

The combination with a skirt having a divided front and a suspended skirt panel attached to the skirt above said divided 65 front, of a removable bloomer panel, de-

tachable means for fastening the rear end of the bloomer-panel at the inside of the skirt, and means for detachably fastening the front end of the bloomer-panel to the front outside of the skirt beneath the skirt panel. 70
